UNITED STATES PATENT OFFICE.

WILLIAM P. WHITLEY, OF ST. LOUIS, MISSOURI, ASSIGNOR TO RAWLINGS MFG. CO.,
OF ST. LOUIS, MISSOURI, A CORPORATION OF MISSOURI.

THIGH GUARD.

Application filed July 11, 1921. Serial No. 433,761.

To all whom it may concern:

Be it known that I, WILLIAM P. WHITLEY, a citizen of the United States, residing at St. Louis, Missouri, have invented a certain 5 new and useful Improvement in Thigh Guards, of which the following is a full, clear, and exact description, such as will enable other skilled in the art to which it appertains to make and use the same.

10 This invention relates to thigh guards, such as are used for protecting the thighs of foot ball players and other athletes from injury.

The type of thigh guard that is now generally used by foot ball players is composed of a number of sections or pieces of rigid material, usually strips of sheet fibre, hinged together by pieces of canvas or other fabric in such a way that they form a guard or 15 shield that has sufficient flexibility to conform approximately to the thigh of the wearer but which is rigid enough to protect the thigh from a blow. While a thigh guard of the construction above referred to 20 affords protection against a blow or a fall, it does afford absolute protection from injury from a cleat of another player's shoe, owing to the fact that the rigid sections of the guard are separated from each other by 25 canvas joints or hinges through which a cleat can easily penetrate.

Therefore, the object of my invention is to provide a sectional thigh guard which is equipped with means for preventing a shoe 30 cleat or other sharp object from passing through the guard at any of the joints or hinges between the rigid sections of the guard.

To this end I have devised a thigh guard 35 that is composed of a number of rigid sections hinged together, and stiff or rigid devices arranged at the joints between said sections in such a way as to prevent a cleat or other sharp object from passing through said joints, but still not interfere with the 40 flexibility of the guard. The guard is adapted to be removably mounted in a pocket or casing in the leg portion of the trousers of the person wearing the guard or it can be 45 permanently combined with the leg portion of the trousers.

Figure 1 of the drawings is a perspective view of a thigh guard constructed in accordance with my invention.

50 Figure 2 is a cross-sectional view of a por-

tion of the thigh guard shown in Figure 1; and

Figures 3 and 4 are cross-sectional views, illustrating modifications of my invention.

In Figure 1 of the drawings which illustrates the preferred form of my invention 60 A designates the rigid sections of a sectional thigh guard, and B designates rigid or stiff protecting devices arranged over the joints or hinges between the sections A of the 65 guard. The guard is preferably composed of two pieces of fabric, usually a piece of canvas *x* that forms the front side of the guard and a piece of felt *y* that forms the inner side of the guard, and strips *z* of sheet 70 fibre or other relatively stiff material arranged in pockets or casings formed by stitching the pieces of fabric *x* and *y* together, thus producing a guard composed of a number of vertically-disposed, rigid 75 sections that are hinged or flexibly connected together. The protecting devices B previously referred to consist of rigid or stiff devices arranged on the front side of the 80 guard over the hinges or joints between the rigid sections A of the guard.

In the form of my invention shown in Figures 1 and 2 each of said protecting devices is formed by a felt strip *w* of fibre or other suitable stiff material arranged in a 85 casing *u* formed by folding and stitching the piece of fabric *x* that forms the front side of the guard, said strip of fibre *w* being wide enough so that it will project laterally over the two adjacent rigid sections A of 90 the guard. Accordingly, the protecting devices B will prevent a shoe cleat or other sharp object from passing through the guard at any of the joints or hinges between the rigid sections of the guard, but they will not 95 interfere with the movement of said sections relatively to each other.

In the form of my invention shown in Figure 3 the protecting devices arranged at the joints between the rigid sections A of 100 the guard are formed by vertically-disposed reeds *w'* arranged in casings *u'* similar to the casings *u* of the guard shown in Figure 2.

In the form of my invention shown in Figure 4 the protecting devices are formed 105 by strips of fibre *w²* of semi-circular shape in horizontal cross section arranged in casings *u²* formed by doubling and stitching the fabric *x* that forms the front side of the guard.

While I have herein illustrated three different ways of forming a thigh guard embodying my invention, I wish it to be understood that my invention is not limited to the particular constructions herein illustrated, as my broad idea consists of a sectional thigh guard composed of a number of rigid sections hinged or joined together in such a way that said sections can move relatively to each other, and stiff or rigid protecting devices arranged on the front side of the guard at the hinges or joints between the rigid sections so as to prevent a shoe spike or other sharp object from passing through the guard at any of the hinges or joints where the rigid sections are united.

Having thus described my invention, what I claim as new and desire to secure by Letters Patent is:

20. 1. A thigh guard composed of a number of stiff sections hinged together; and stiff protecting devices separate and distinct from said sections arranged at the front side of the guard and extending longitudinally of the joints between said sections for preventing a sharp object from penetrating or passing through any of said joints.
25. 2. A thigh guard composed of a number of stiff sections, hinges between said sections, and stiff protecting devices arranged on the front side of the guard over the joints between said sections and capable of moving independently of said sections.
30. 3. A thigh guard composed of a number of pieces of relatively stiff material arranged vertically in parallel relation and spaced apart, and stiff protecting devices arranged

at the front side of said guard so that they will prevent a shoe spike or other sharp object from passing through the joints between said pieces. 40

4. A thigh guard composed of a fabric structure provided with a set of relatively large pockets and a set of relatively small pockets arranged in alternate relation, pieces 45 of stiff material positioned in the large pockets, and substantially rigid protecting devices positioned in the small pockets, for the purpose specified.

5. A thigh guard, comprising a fabric 50 structure, pieces of substantially rigid material arranged in said structure and separated from each other by joints, casings in said fabric structure located on the front side of the guard at said joints, and rigid 55 protecting devices arranged in said casings, for the purpose described.

6. A thigh guard composed of two pieces of fabric joined together to form a series of large pockets, and a series of small 60 pockets arranged between said large pockets, flat strips of fibre arranged in said large pockets, and substantially rigid protecting devices arranged in said small pockets, for the purpose specified. 65

7. A thigh guard composed of a number of rigid sections connected together by flexible hinges, and rigid protecting devices arranged on the front side of the guard in overlapping relation with said hinges so as 70 to prevent a shoe spike or other sharp object from penetrating said guard at the joints between said rigid sections.

WILLIAM P. WHITLEY.

Certificate of Correction.

It is hereby certified that in Letters Patent No. 1,428,731, granted September 12, 1922, upon the application of William P. Whitley, of St. Louis, Missouri, for an improvement in "Thigh Guards," an error appears in the printed specification requiring correction as follows: Page 1, line 26, after the word "does" insert the word *not*; and that the said Letters Patent should be read with this correction therein that the same may conform to the record of the case in the Patent Office.

Signed and sealed this 31st day of October, A. D., 1922.

[SEAL.]

KARL FENNING,

Acting Commissioner of Patents.
